CLAIM

The ornamental design of a suction coagulator, as shown and described.

DESCRIPTION

FIG. 1 is a top, front and right side perspective view of a suction coagulator according to the design of the present invention;

FIG. 2 is a right side elevation view of the design depicted in FIG. 1;

FIG. 3 is a top plan view of the design depicted in FIG. 1; FIG. 4 is a bottom plan view of the design depicted in FIG. 1;

FIG. 5 is a front elevation view of the design depicted in FIG. 1; and,

FIG. 6 is a rear elevation view of the design depicted in FIG. 1.
